UNITED STATES PATENT OFFICE

OLLIE P. PERRY, OF JACKSON, KENTUCKY

RAILWAY CAR BRAKE

Application filed May 19, 1928. Serial No. 279,063.

My present invention relates to improvements in railway car brakes of the automatic type, which while adapted for use on railway cars generally, are particularly designed for use on cars employed in industrial plants, as for instance on mining cars. The primary object of the invention is the provision of means actuated from a track-side installation for applying the brakes to the wheels of the car as the latter runs on a down grade. In carrying out my invention the brakes are applied to retard the descent of the car down the grade, and means are provided for applying the brakes at the top of the grade, and then for releasing the brakes at the bottom of the grade. The track-side installation includes a trip device situated at the top of the grade, and a similar trip device located at the bottom of the grade, which devices successively contact with operating means carried by the car for partially applying the brakes on the car, and then for releasing the brakes from the wheels. As is well known in mining operations the loaded car passes over the rails in one direction, and returns empty in the opposite direction, and therefore the track-side installation is employed in connection with the rails over which the loaded car passes as it descends the grade. By means of the brake operating mechanism the progress of the loaded car down hill is retarded, and as the car approaches the bottom of the grade the brakes are released to permit the car to gain sufficient momentum to insure its further progress along the tracks.

In the accompanying drawings I have shown a car with two two-wheel trucks and the brakes are applied to the four wheels. It will be understood that the number of brakes employed may be increased or diminished as desired, and while I have shown the track-side installation at the right side rail, it will be understood that the trips may be duplicated at the left hand side rail, and the brake applying levers as well as the brake release may be situated at one or both sides of the car, depending upon conditions

to be met in connection with the railway and its rolling stock.

The invention consists in certain novel combinations and arrangements of parts as will hereinafter be more fully set forth and claimed. 55

In the accompanying drawings I have shown one complete example of the physical embodiment of my invention wherein the parts are combined and arranged according to the best mode I have so far devised for the practical application of the principles of my invention. 60

Figure 1 is a view in side elevation showing a car equipped with the brake mechanism of my invention the car traveling in the direction of the arrow and having its brakes partially applied to retard its progress. Figure 2 is a view similar to Figure 1 with the car traveling in the direction of the arrow after its brakes have been released. Figure 3 is a top plan view of the braking mechanism, some parts being shown in section. Figure 4 is a vertical sectional view at line 4—4, of Figure 1. Figure 5 is a detail view partly in section of one of the resilient couplings for the brake. Figure 6 is a view in elevation of one of the trips, showing the rail in section. Figure 7 is a side view of the device of Figure 6. 65 70 75 80

In order that the general arrangement and relation of parts may readily be understood I have shown a well known type of car C having the usual wheels W journaled on the axle A, and the rails are designated R. 85

The breaking mechanism is shown at each side of the car and applied to each of the four wheels. A usual type of brake shoe 1 is employed for each wheel and the shoes are suspended by links 2 from the horizontal bracket arms 3 which are bolted at each side of the car body. The bracket arms each have a central hanger 4 for the rock shaft 5 which is disposed transversely of the car between the two axles and journaled in bearings 6 of the hanger. 90 95

Upon the ends of the rock shaft are provided double crank arms 7 which are keyed on the shaft, and these crank arms are provided with slotted ends and joined by ex- 100

tensible, adjustable, resilient, couplings, to the brake shoes. These couplings are designated as a whole by the letters B and D.

As shown in Figure 5 each of the couplings includes a bolt 8 that telescopes in the tubular screw bolt 9, and the bolt 8 is fashioned with an end ring 10 pivoted to the brake shoe, and this bolt also has an end cup or hollow head 11. A spring 12 is coiled about the coupling and interposed between the cup 11 and a washer 13 on the tubular screw bolt, and lock nuts 14 on the screw bolt are used to vary the tension of the spring and to take up or compensate for wear of the parts. The tubular screw bolt has an eye 15 which is pivoted to one of the double crank arms on the rock shaft. In Figure 1 the double crank arm 7 is in position to partially apply the brake shoes 1 to the wheels, and the resilient couplings B and D hold the brake shoes in their partially applied position. In Figure 2 the double crank arm is swung to released position, and the resilient couplings hold the brake shoes in this position, the links 2 hanging in vertical position from the bracket arms 3. The parts are shown in normal position in Figure 2, while they are shown with the brakes applied or partially applied in Figure 1.

A brake lever 16 is used at one or both sides of the car and this lever is fixed to the rock shaft 5 in position to be tripped as it encounters or contacts with a trip roller 17 of the track-side installation.

The roller 17 is located at the inside of the rail and is journaled in a spring pressed bolt 18 which telescopes in a socket arm 19 that is pivoted at 20 to the base plate 21. Any usual means, as a pin and slot arrangement may be used to maintain the proper relation between the roller and the socket arm, and the base plate 21 has a stop arm 22 which holds the roller in uplifted position when it is struck by the brake lever, and a spring 23 returns the roller to upright position after it has been swung to dotted line position in Figure 7 by the brake lever on an empty car that may be passing in the direction opposite to the movement of the loaded car.

The base plate 21 is fastened to the base flange of the rail R and for this purpose is fashioned with a bolt 24 over which the flanged plate 25 is fitted against the rail flange, and a nut 26 clamps the plate 25 on the rail flange. Two trip devices are employed, one being located at the top of the down grade to apply the brakes, and the other located near the bottom of the descent in order to release the brakes.

The car is equipped with one or more release levers 27 adapted to encounter a roller 17, and the lever 27 is designed to rock the shaft 5 in direction opposite to the movement imparted thereto by the brake lever

16. For this purpose the release lever 27 which is pivoted at the under side of the car body at 28 is provided with a link 29, and the link is pivoted to a crank arm 30 located on the rock shaft 5 and projecting upwardly 70 therefrom.

It will be understood that the brake mechanism is designed to apply the brakes as the car starts to descend a grade, and after the car reaches a level stretch of track, the 75 brakes are disengaged. In Figure 1 the lever 16 has contacted with its complementary trip lever 17, and the brakes are applied. In Figure 2 the release lever 27 has contacted with the trip lever 17, and the 80 brakes are disengaged.

When lever 16 struck the trip lever 17 the shaft 5 and double crank arm 7 were rocked from position of Figure 2 to that of Figure 1, causing the couplings B and D to swing 85 the brake shoes against the wheels of the car.

When release lever 27 struck the trip lever 17 the shaft and crank arm were rocked in the opposite direction, and couplings B and D therefore withdrew the shoes from the 90 wheels.

The operating movement of the brake applying mechanism may be varied for the purpose of varying the degree of pressure of the brake shoes against the wheels. For this purpose I provide a stop lug 31 fixed on the hanger 4 and a control arm 32 which is fixed to rock with the shaft 5 is provided with flanged ends in which the stop bolts 33 are threaded. These bolts are designed to alternately contact with the stop lug 31 and limit the rocking movement of the shaft 5. It will be apparent that the range of movement of the arm 32 may be increased or diminished by adjusting the bolts 33, and thereby the pressure of the brake shoes may be controlled. The brake shoes may be applied either to retard the progress of the car, or the brakes may be applied to stop 100 the car if desired.

Manually operated means are shown for applying or releasing the brakes, which means include a hand rod 34 located at one side of the car and pivoted to the crank 105 arm 30. In some instances this rod may be employed to apply or release the brakes.

Having thus fully described my invention, what I claim as new and desire to secure by Letters Patent is:—

1. The combination with a pair of brake shoes and a rock shaft of a double brake arm on the shaft and resilient couplings between said arm and shoes, a brake lever on the shaft, a release lever connected with the 115 shaft, a hanger for the shaft and a stop lug thereon, and a control lever on the shaft for co-action with said stop lug.

2. The combination with a pair of brake shoes and a rock shaft and resilient cou- 130

plings between said shaft and shoes, of a
brake lever, a release lever, a hanger for the
shaft and a stop lug on the hanger, a con-
trol lever on the shaft having flanged ends,
5 and bolts in said ends for co-action with
said lug.

3. The combination in a railway car brake
mechanism and operating means therefor,
10 of a pair of brake shoes and an intermediate
rock shaft, a double brake arm on the shaft,
and resilient couplings between said shoes
and arm comprising telescoping spring
pressed bolts.

4. The combination in a railway car brake
15 mechanism and operating means therefor, of
a pair of brake shoes and an intermediate
rock shaft, a double brake arm on the shaft,
and resilient couplings between the shoes and
arm each comprising a tubular, threaded bolt
20 and a telescoping bolt, a spring interposed
between portions of said bolts, and an ad-
justing nut on the tubular bolts.

In testimony whereof I have affixed my
signature.
